UNITED STATES PATENT OFFICE

JAMES E. SPENCE, OF WHEELING, WEST VIRGINIA, ASSIGNOR TO HAZEL-ATLAS GLASS CO., OF WHEELING, WEST VIRGINIA, A CORPORATION OF WEST VIRGINIA

DESIGN FOR A DRINKING GLASS

Application filed October 15, 1931. Serial No. 41,393. Term of patent 3½ years.

To all whom it may concern:

Be it known that I, JAMES E. SPENCE, a citizen of the United States, residing at Wheeling, in the county of Ohio, and State of West Virginia, have invented a new, original, and ornamental Design for Drinking Glass, of which the following is a specification, reference being had to the accompanying drawing, forming part thereof.

The figure is a perspective view of a drinking glass, showing my new design.

The dominant feature of my design resides in the shape or contour of the drinking glass.

I claim.

The ornamental design for a drinking glass, as shown and described.

JAMES E. SPENCE.
